UNITED STATES PATENT OFFICE.

WILLIAM GEE, OF NEW YORK, N. Y.

APPARATUS FOR DISPENSING EFFERVESCENT DRINKS.

SPECIFICATION forming part of Letters Patent No. 410,514, dated September 3, 1889.

Application filed May 23, 1889. Serial No. 311,848. (No model.)

To all whom it may concern:

Be it known that I, WILLIAM GEE, a citizen of the United States, residing at New York, in the county of New York and State of New York, have invented new and useful Improvements in Apparatus for Dispensing Effervescent Drinks, of which the following is a specification.

My invention relates to apparatus for dispensing effervescent drinks at retail, such as soda and mineral waters.

It is my purpose to provide a simple, convenient, and ornamental structure, forming a container for the ice and pipe-coils and surrounded by a cap supporting the faucets, said cap forming the pivotal seat for a revolving siruping apparatus having a central ice-chamber, from which the ice-water is discharged upon the inner wall of the ice-chamber in the container below, whence it is carried off by any suitable waste-pipe.

It is my purpose, also, to provide simple means whereby the valves of the sirup-jars may be readily operated, the construction being such as to permit a uniform and compensating adjustment of the parts and allow their easy removal and restoration to place, the entire sirup-casing being also rendered removable and separable to permit its thorough cleansing.

It is one purpose of my invention, also, to provide a novel and simple construction and combination of parts, whereby any one of the sirup-jars may be removed from the casing in which it is supported without uncovering said casing, and whereby, also, it may be refilled from its bottom, which is normally inverted and so constructed as to provide a separable bearing for the valve-stem.

It is my purpose, finally, to simplify and improve the construction and operation of apparatus of this class to render it convenient, compact, and of ornamental proportions and appearance, and to adapt the parts to effect this cooling of the soda and of the sirups rapidly and economically, while the apparatus as a whole shall be so organized that it occupies a comparatively small space and may be constructed at a considerably reduced cost.

Referring to the accompanying drawings, Figure 1 is a sectional elevation showing an entire apparatus constructed in accordance

with my invention. Fig. 2 is a horizontal section in the line $x x$, Fig. 1. Fig. 3 is a sectional plan view of the siruping apparatus. Fig. 4 is a detail view of one of the supporting columns or brackets removed from the siruping apparatus. Fig. 5 is a detail section of the lower part of one of the sirup-jars. Fig. 6 is a view of a sirup-jar, showing a modified construction.

In the drawings, the reference-numeral 1 denotes the marble or other shelf, counter, or support upon which the apparatus is placed. Upon this support rests a base 2, having a central depending stem or nipple 3, which passes down through an opening in the counter and serves as a discharge for waste water. Surrounding the base 2 is a flange 4, within which is inserted the base of the cylindrical body 5, which is formed of sheet metal and provided with a double wall forming an annular dead-air space, which prevents the rapid conduction of the reduced temperature within or the higher temperature outside. The body portion is provided with a door 6, having a similar construction for the introduction of the ice, and a shield 7 is attached to its inner wall to protect the pipe from injury when the ice is thrown in.

Upon the upper end of the cylindrical body rests a cap 9, formed preferably of cast metal and provided with a ring 10, which supports one or more faucets 12, connected to the pipes emerging from the shield 7. This cap is held in place by tie-rods 13, passing up through the base 2 and through inwardly-projecting lugs 14 on the cap, nuts being turned on the ends of said rods above the lugs. A washer 15, of leather, rubber, or other suitable material, is slipped upon each tie-rod and lies between its head and the base 2, thereby forming a tight joint and preventing leakage through the openings made for the tie-rods.

Upon the ring 10 is placed a cover 16, having a threaded flange 17 screwed within the ring. Upon the elevated central portion of this cover is formed a seat 18, having a central vertical stem or pivot 19, and provided below the base of the latter with a circumferential cup-shaped flange 20, apertures 21 being formed in the metal of the seat leading from the inner and lower parts of the cup to the inside of the cover, where they discharge

into a diverting-passage 22, having its discharge end adjacent to the inner face of the cover.

In order to firmly connect the base 2 and 5 the parts mounted thereon firmly to the counter, the nipple or stem 3 is threaded and receives a nut 23, which is turned up against the lower face of the counter. A surrounding and projecting foot-plate 24 is also formed 10 upon the base of the body portion and extended to rest on the counter at a little distance from the base 2, inclosing an air-space 25.

Upon the seat 18 rests the siruping apparatus, which is contained within a casing of circular form having a base 26, provided with a central buttress 27, in which is mounted a socket 28, the stem 19 passing through an opening in the buttress 27 and lying in the 20 socket. Openings 29 are formed in the base at suitable intervals surrounding the buttress 27, for the discharge of the water formed by melting ice and condensation, said openings discharging into the cup 20.

25 The base 26 is formed preferably of a single casting provided with a hanging circumferential flange 30. Upon this base, at a point between its axial center and its periphery, is placed a circular wall 31, having perforations 32, and rising to a suitable height to form a central ice-chamber. The annular space outside this wall is inclosed in the following manner: Surrounding the base is a peripheral channel 33, and rising from said 35 base at suitable intervals are columns or brackets 34, having substantially a T shape in cross-section, the central arm thereof projecting inward or toward the center. At the bottom and top of each column are formed 40 horizontal plates 35, through which pass bolts or screws firmly connecting said columns to the base 26, the arrangement being such that the flat-vertical plate of each column is flush with the inner wall of the channel 33. At 45 their upper ends they are attached to a horizontal flange 36, which projects from the inner wall 31, and is provided with openings 37, formed between the radial lines drawn from the center through each column. The 50 top is covered by an annular cap 38, having double walls inclosing a dead-air space. This cap is provided with an inwardly-projecting flange 39, which rests upon the top of the wall 31, while the periphery is seated in recesses 55 40, formed in the outer faces of the columns 34 at their top.

The spaces between the several columns or brackets 34 are closed by panels 41, which have their lower edges placed in the channel 33, 60 while their upper edges lie under that portion of the edge of the cap 38 which projects outward from the recesses 40 in the columns. From the inner face of each panel, near its vertical edges, project flanges or tangs 42, 65 which extend inward and are then bent toward each other. These flanges engage grooves 43, formed in the glass sirup-jar 44,

but terminating a short distance from its inverted bottom, thus enabling said flanges to support the entire weight of the jar by which 70 the panel is held closely and firmly in position. Upon the outer face of each panel is formed or mounted a lift 45, which also serves to display the name of the sirup contained by the jar within.

75 Each sirup-jar is preferably of the form shown in Fig. 3, whereby it nearly fills the space within which it lies and affords storage to the required quantity of sirup. Each jar is provided with a neck or top 46, which is externally threaded, and the jar being inverted when mounted upon the panel 41 this neck projects downward and through an opening 47 in the base 26, said opening being surrounded by a circular flange 48 to prevent 85 the escape of water formed by condensation. Upon the projecting neck is screwed a cap 49, within which is placed a glass valve-seat 50, which is held by the cap closely against the open end of the neck. With this 90 valve-seat engages a cone-shaped plug-valve 51, having a rubber facing 52 and carried by a stem 53, which rises within the jar and projects above its inverted bottom, which is formed of two unequal pieces of glass or metal 95 54 and 55, each having a half socket or bearing 56 for the valve-stem. Both of the parts forming the bottom of the jar may be removed for cleansing purposes.

Upon the projecting end of the valve-stem 100 53 is formed a screw-thread, and a weight 57 is turned thereon, by the gravity of which the valve is seated. It is lifted by a lever 58, having an angle or crook, whereby, when inserted 105 through an aperture 59 in the panel, said lever requires no fulcrum-pin, but rests upon the edge of the opening in which it lies. The weight end of the lever is forked and embraces the valve-stem 53 below the weight 57. This weight being capable of adjustment 110 upon the stem, the power end of the lever may be raised to the proper point to enable it to have the desired operation, and in like manner a uniform and compensating adjustment may be given to all the levers, whereby 115 the external appearance of the apparatus is much improved.

The ice-chamber of the sirup apparatus is closed by a cover 60, also provided with a dead-air space. This cover rests directly 120 upon the flange 39 of the annular cap 38. Openings 61 are formed in the inner wall 31, next to the base on which it rests, to allow the water of condensation to flow to the discharge-openings 29.

125 The sirup-jars may be filled or inspected by simply tilting the panels one at a time outward. This is effected by taking hold of the lift 45 and drawing the panel outward, whereupon the top swings toward the operator, the panel turning upon its lower edge, which lies in the channel 33. In this manner the jar is exposed without removing the cap or cover. I may, however, make the panels

a rigid portion of the frame or casing, and in this case the jars would be removed by taking off the cover, inserting the hand, removing the inverted bottom part 54 of the jar, and 5 allowing the valve-stem to swing inward. The lever is then withdrawn from its aperture, and the jar may then be taken out.

The casing containing the sirup apparatus may be round, polygonal, or square, without 10 substantial modification of my invention in other particulars, and my invention may be applied to an immovable casing, wherein all the panels are arranged to form a continuous straight or curved front. The panels may be 15 plated with silver or nickel, or otherwise ornamented in any suitable manner. They may be formed, also, of metal or other material—such as tiling—painted or decorated and inclosed in a metallic frame which supports 20 the jar, and which may be plated.

The cover 16 and seat 18, with its cup-flange 20 and stem 19, are all cast in a single piece.

In forming the jars which contain the sirup ribs 62 may be molded upon their outer faces 25 in place of the grooves 43, and these ribs will lie between the flanges or tangs 42 and the panels. When these ribs are substituted for the grooves, lugs will be formed upon their 30 ends to engage with and rest upon the upper ends of said flanges in order to throw the weight of the jar upon the panel.

What I claim is—

1. In apparatus for dispensing effervescent drinks, the combination, with a container 35 having an ice-chamber in which the coils are arranged, of a supporting cap or cover having a seat, a stem or spindle, and a cup-flange, all formed in one casting, and a rotating sirup apparatus contained in a casing pivotally 40 mounted upon said seat and stem, substantially as described.

2. In an apparatus for dispensing effervescent drinks, the combination, with an ice-container in which the pipe-coils are arranged, 45 of a cap or cover having a seat, a stem or spindle, and a flange, all formed of a single integral casting, a sirup apparatus contained in a casing pivotally mounted upon said stem and seat and having openings in 50 its base discharging into the cup-flange, and thence through openings in the seat into or upon a diverting-plate which conducts the drip to the inner face of the container, substantially as described.

55 3. In an apparatus for discharging effervescent drinks, a sirup apparatus contained within a casing or chamber inclosed in front by a series of panels resting at their lower ends within a circumferential rib or flange, 60 and upon the inner faces of which the sirup-jars are detachably mounted, substantially as described.

4. In an apparatus for dispensing effervescent drinks, the combination, with the casing, 65 of a series of separate panels resting at their lower ends within a channel on the base of

the casing, each panel being provided on its interior face with flanges or tangs, and sirup-jars having grooves terminating at a short distance from their inverted bottom, and in 70 which the flanges lie, substantially as described.

5. In apparatus for dispensing effervescent drinks, the combination, with a casing, of a series of separate panels inclosing its front, 75 each panel having its lower edge lying in a channel in the base of the casing, a series of inverted sirup-jars detachably mounted upon the inner faces of said panels and having valves carried by stems projecting through 80 their inverted bottoms, and weights adjustably mounted on the projecting ends of the valve-stems, and actuating-levers inserted through openings in the panels and engaging the valve-stems beneath said weights, substantially as described.

6. In apparatus for dispensing effervescent drinks, the combination, with a casing, of a series of separate panels inclosing its front, a series of inverted sirup-jars detachably 90 mounted on the inner faces of said panels, their necks projecting through openings in the base or floor of said chamber, a series of valves carried by stems which lie within and project above the inverted bottoms of the 95 jars, each bottom being formed of two removable parts, each part having a half socket or bearing for the valve-stem, weights screwed upon the threaded projecting ends of the valve-stems, and a series of levers inserted 100 through openings in the panels and resting upon the edges of said openings, said levers engaging the valve-stems beneath the weights, substantially as described.

7. In an apparatus for dispensing effervescent drinks, the combination, with a casing, of a panel inclosing its front and resting at its lower end in a channel in the base of the casing, a sirup-jar having grooves in its body engaging flanges on the inner face of said 110 panel, by which the jar is entirely supported, a screw-cap containing a valve-seat and turned upon the inverted neck of the jar, which projects through an opening in the base of the casing, a rubber-faced valve engaging 115 said seat and mounted on a stem passing through the removable two-part bottom of the inverted jar, a weight turned upon the threaded projecting end of said stem, and a lever inserted in an opening in the panel and 120 engaging the stem below the weight, substantially as described.

8. In an apparatus for dispensing effervescent drinks, the combination, with a pivotal support, of a casing for the sirup apparatus having a circular base provided with a peripheral channel and having at intervals a series of columns or brackets arranged within said channel and connected by screws or rivets to the base and to a sectional flange 125 above, and a series of panels having their lower ends resting in said channel and their

vertical edges overlying the outer faces of the columns, substantially as described.

9. In an apparatus for dispensing effervescent drinks, the combination, with a container having a suitable ice-chamber within which the pipes are cooled and provided with a support or cover having a stem or pivot, of a stirring apparatus contained within a casing pivotally mounted upon said stem and sup-

ported by the container, substantially as described.

In testimony whereof I have affixed my signature in presence of two witnesses.

WILLIAM GEE.
